UNITED STATES PATENT OFFICE.

ZEBULON LINCOLN CHADBOURNE, OF NEW BRIGHTON, NEW YORK.

FINGER MECHANISM FOR LOOMS.

SPECIFICATION forming part of Letters Patent No. 724,260, dated March 31, 1903.

Application filed September 28, 1901. Serial No. 76,871. (No model.)

To all whom it may concern:

Be it known that I, ZEBULON LINCOLN CHADBOURNE, a citizen of the United States, residing at New Brighton, in the county of 5 Richmond and State of New York, have invented new and useful Improvements in Finger Mechanism for Looms, of which the following is a specification.

My invention relates to a finger mechanism 10 for engaging the weft-threads on a loom for open-meshed fabrics such as is covered by my application Serial No. 59,118 and raising these weft-threads up into position to be caught by the pins on the pin-roller to form 15 crosses with the said warp-threads.

The novel construction employed is fully described in this specification and claimed, and illustrated in the accompanying drawings, forming a part thereof, in which—

20 Figure 1 is a side elevation of the front portion of a loom with parts broken away and with my device secured thereto. Fig. 2 is a plan view of the same. Fig. 3 is a fragmentary detail of one of the rock-shafts.

25 Like numerals of reference designate like parts in the different views of the drawings.

The numeral 1 designates the side frame of my loom, and 2 the main driving-shaft. A double series of horizontal pins 3 are 30 mounted in rails 4, extending transversely the machine. A set of shuttles 5 are mounted on the pins 3 and each carries one end of a weft-thread A, which pass up and over a pin-roller 6, mounted to be revolved and to 35 be reciprocated endwise. A tension-bar 7 is mounted parallel to the pin-roller 6 and in combination therewith supports warp-threads B. The tension-bar 7 is mounted to be reciprocated longitudinally in unison with the pin- 40 roller, and the warp thereby moved bodily in its own plane a distance of two threads of the warp at each movement. After each movement of the warp the shuttles 5 are passed therethrough and cross the weft and 45 warp threads. After each movement of the warp the pin-roller is turned to engage the weft-threads and form crosses.

All of the above description applies to my loom and is no part of my present invention. 50 In using the loom constructed as above set forth I found that the crosses of the threads did not come within reach of the pin-roller,

and some mechanism was necessary to beat the crosses back—that is, raise them up into position to be engaged by the pin-roller. In 55 other words, since the warp-threads were only moved a distance of two threads relative to the shuttles the weft-threads only crossed two warp-threads in the distance between the pin-roller and the shuttle. So in order to form 60 the crosses it would be necessary to wind up the whole length intervening between the pin-roller 6 and the shuttles after each shift of the pin-roller and tension-bar. This is avoided by the finger mechanism. This mech- 65 anism forms the subject-matter of the present application.

Rigidly secured to the frames 1 in front of the pin-rollers 6 are apertured arms 9, within which is journaled a rock-shaft 10, bearing a 70 crank-arm 11. Mounted in the rock-shaft 10 is a series of parallel fingers 12 for engaging the weft-threads when in their forward position, (shown by dotted lines marked A,) each of the fingers 12 consisting of two parallel 75 members having their ends turned out at 12°. A connecting-rod 13 is pivoted at its upper end to the crank-pin 11^a and at its lower to the long slotted arm of a lever 14, fulcrumed on a stud seated in the frame. The short 80 arm of the lever 14 is slotted and pivoted to the upper end of a pusher-rod 15, mounted in a guide 16, formed on an arm 15^a, secured to the frame 1. This pusher-rod 15 is provided with a roller 16^a, journaled in its lower end and 85 located to be engaged by two arms 17^a of a four-armed cam 17, keyed on the main shaft 2.

Located just back of the pin-roller 6 is a mechanism similar to the one just described 90 and comprising a rock-shaft 18, bearing fingers 19, which rock-shaft is provided with a crank-arm 20, connected to the long arm of a lever 21 by means of a rod 22. The short arm of the lever 21 is pivoted to a pusher-rod 22^a. 95 This pusher-rod 22^a has a roller 23 journaled therein, which is in position to be engaged by two arms 17^b of the four-armed cam 17. The arms 17^a and 17^b alternate, so that the pushers 22 and 15 are operated alternately. 100 Springs 24 are connected to the frame 1 and to the long arms of the levers to restore them to their initial position after each displacement.

The operation of my device can now be sketched. When the shaft 2 revolves, the arms 17^a and 17^b alternately operate the levers 14 and 21 to operate the rock-shafts 10 and 18 to raise the fingers 12 and 19. The cam is set so that the fingers 12 will be raised to engage the weft-threads to throw the portion intervening between the shuttles and fingers parallel to the warp-threads as viewed 5 from the front and throw the remaining part of the weft intervening between the fingers and the pin-roller 6 into a position transverse to the warp. When the fingers 12 have reached the uppermost position, this latter 10 intervening length is very short and is picked up by the next partial revolution of the pin-roller 6. The fingers 19 are raised to engage the weft when the shuttles are in their rear position. By this means the action of my 15 loom is made more positive than before.

I do not wish to be limited as to details of construction, as these may be modified in many particulars without departing from the spirit of my invention.

Having thus described my invention, what I claim as new, and desire to secure by Letters Patent, is—

1. The combination with a pin-roller mounted to be revolved and to move longitudinally, 20 a tension-bar, said roller and said tension-bar being constructed to carry a series of warp-threads and one of the ends of a series

of weft-threads which are arranged on said pin-roller alternately with said warp-threads, shuttles carrying the other ends of said weft-threads, means for passing said shuttles through the plane of said warp, means for moving said pin-roller and said tension-bar longitudinally after each movement of said shuttles to throw said weft-threads out of parallel with said warp-threads, fingers mounted to engage said weft-threads, and means for operating said fingers to engage said weft-threads to bring them parallel with said warp-threads after each longitudinal movement of 35 said pin-roller and tension-bar, substantially as described.

2. The combination with means for holding the lay of the warp and one end of the lay of the weft, shuttles carrying the other end of 50 the weft, means for intermittently moving said shuttles, means for moving the warp transversely, fingers each formed of two parallel members and located to engage the weft, and means for operating said fingers, substantially as described.

In testimony whereof I have hereunto set my hand in presence of two subscribing witnesses.

ZEBULON LINCOLN CHADBOURNE.
